UNITED STATES PATENT OFFICE.

CHARLES HOLLIWELL, OF BROADHEATH, AND MATTHEW HENRY WHITTAKER, OF MANCHESTER, ENGLAND, ASSIGNEES TO LINOTYPE AND MACHINERY LIMITED, OF LONDON, ENGLAND.

TYPOGRAPHICAL CASTING-MACHINE.

1,193,264.

Specification of Letters Patent. Patented Aug. 1, 1916.

Application filed December 1, 1914. Serial No. 874,960.

To all whom it may concern:

Be it known that we, CHARLES HOLLIWELL and MATTHEW HENRY WHITTAKER, subjects of the King of the United Kingdom of Great Britain and Ireland, and residing, respectively, at Linotype and Machinery Works, Broadheath, in the county of Chester, England, and Norton House, Hornby Road, Old Trafford, Manchester, in the county of Lancaster, England, have invented new and useful Improvements in or Relating to Typographical Casting-Machines, of which the following is a specification.

This invention relates to typographical casting machines, particularly those known commercially under the trade mark "linotype," and it has for its object to provide means whereby, for particular classes of work involving the casting of type bars of different body dimension, the trimming knives can be automatically adjusted in accordance with those body dimensions.

Among the abovenamed classes of work in connection with which the present invention could be advantageously employed, there may be mentioned the casting of type bars, hereinafter termed "slugs," suitable for the printing of Christmas cards, and auctioneers' and various other catalogues, in which one item such for example as, in the case of a Christmas card, the name of the sender would be printed in larger type than would be the address or legend appearing on that card.

The different sized slugs, say two sizes, involved in the use of this invention, would both be cast in the same mold, the cap of which would be grooved to a depth which, measuring from the bottom of those grooves to the opposed face of the mold body, would respond with the body dimension of the slug suited to carry the characters of the largest body dimension, and the distance between the surface of the mold cap between those grooves and the said opposed surface of the mold body would represent the body dimension of the slug appropriate to the type characters of smallest body dimension. Such an arrangement as that is already well known in the art, and has been fully described in Letters Patent No. 665,912. There have also heretofore been known trimming knives which have been longitudinally adjustable to avoid the shearing

off of what have, in the past, been termed two-line letters, and the present invention involves the use of a trimming knife adjustable in substantially the same manner. Heretofore these two-line letter knives have had their longitudinal motion restricted by their paths being intercepted by the two-line letters which it was intended should be retained on the slug, and which letters, if the movement of the knife were not so restricted, would have been shorn off by that knife.

The present invention involves among other new features, novel means whereby a knife previously set for trimming slugs of one body dimension, can be released, by overhanging projections cast on the slug, to allow it to assume the position necessary for trimming slugs of another body dimension, but these projections unlike the before-mentioned two-line letters, are provided solely for the purpose of controlling the adjustment of the knife and are shorn off by the latter after they have fulfilled that function.

The invention will now be described by reference to the accompanying drawings in which:—

Figure 1 is a front elevation of sufficient of a typographical casting machine to show the application thereto of the present invention; Figs. 2 and 3 are plans of Fig. 1, showing the devices at respectively different stages of their operation. Fig. 4 is a perspective view of the improved movable knife; Fig. 5 is a perspective view and Fig. 6 an elevation of one of the improved character matrices; Fig. 7 is an elevation of one of the improved en spaces; Fig. 8 is a perspective view of one of the slugs with the overhanging knife-releasing projection still intact therewith; Fig. 9 is a plan showing one construction, Fig. 10 a plan and Fig. 11 an elevation showing another construction, and Fig. 12 an elevation showing a third construction of adjustable movable knife according to this invention.

The parts of the machine illustrated in the drawings which are of ordinary construction, and thus constitute no feature of the present invention, are, by way of distinction, indicated in chain or dotted lines.

According to the present invention, the adjustable knife, which, as a complete en-

ity, is hereinafter identified by the reference numeral 1, is formed in what may be regarded as two sections, these in Fig. 4 being clearly distinguishable by the numerals 2, 3 respectively, the trimming edge of the section 3 being in advance of that of the section 2 and serving for trimming slugs of smaller body dimension than those to be trimmed by the section 2. By the term "in advance" as just employed is meant a position nearer to the stationary or fixed knife 4 (Figs. 1, 2 and 3). In the arrangement illustrated and as just described, it is the upper section 3 of the knife 1 which serves for trimming slugs of smaller body dimension, and the section 2 that which serves for trimming slugs of a larger body dimension, and this is the preferred arrangement, but the reverse of that arrangement may, if desired, be employed. The two sections 2, 3 are separated by a gap 5 which enables the two sections 2, 3 to be more easily ground than would be the case were they joined to each other at an abrupt angle.

25 The knife 1 is arranged to slide vertically in a guide block 8 so as to bring one or the other of its sections into active position or opposite the stationary knife 4, a spring 1^a tending constantly to raise the knife to its uppermost position, and a bar 1^b, connected to the lower end of the knife and actuated by some suitable part of the machine, being adapted to return the knife to its lowermost position against the action of the spring.

35 The knife 1 has fixed to it a laterally extending stud 6 (Figs. 1, 2 and 3) which is capable of moving in a vertical groove 7 in a guide block 8 in which the knife 1 is capable of sliding in a vertical direction in response to the action thereon of the aforesaid cam and spring. The guide 8 is, in the usual manner, attached to the so-called knife-block 9 which is in turn attached to the vise frame 10, to which also as ordinarily is secured the before-mentioned stationary knife 4.

At the rear of the groove 7 there is provided a horizontal sliding latch 11 which can be projected into the groove, as shown in Fig. 2, and withdrawn from it as shown in Fig. 3, for engaging with the stud 6, as shown in the former figure, and releasing it as shown in the latter figure. When the latch 11 projects into the groove 7 above the stud 6 the movable knife 1 is held by the engagement of the former with the latter in its depressed position, as indicated best in Fig. 2, and it is while the knife is in that position that it effects the trimming of the slugs bearing characters of the smaller body dimension; so long as this engagement of the latch 11 and stud 6 continues, the section 2 of the knife cannot come into operation, but when the latch 11 is withdrawn into the position in which it is shown in Fig. 3, the

knife 1 is raised by the aforesaid spring and the section 2 thereof is thereby brought into operative position to trim slugs bearing characters of the larger body dimension.

The sliding latch 11 is in pivotal connection with a plate 12 adapted to turn about the vertical pivot 13 in fixed relationship to the guide block 8, this pivotal connection being effected by forming a nick or reduced portion of the latch 11 which is embraced by a slot 14 in the plate 12. A blade spring 15 fastened at one end to the guide block 8, bears at its other end on the rear end of the latch 11 in such manner as to constantly tend to hold the latch in, or return it to, its normal foremost position in which it is in engagement, or ready to engage, with the stud 6. The forward end of the latch 11 is inclined at its upper side as indicated at 16 in Fig. 2, so that when the stud 6, during the descent of the knife 1, moves into contact therewith (the said latch being then in its foremost position) it, the stud, pushes the latch 11 rearwardly out of its path, and the said latch after the stud has thus descended past it is immediately returned by its spring 15 into its foremost position to again operate to prevent the knife 1 reaching its higher position. The forward movement of the latch 11 under the action of the spring 15 is limited by the right-hand edge of the plate 12, which, by abutting against the rear side of the guide block 8, as indicated in Fig. 2, serves as a stop for this purpose. The left-hand edge of the pivoted plate 12 normally occupies a position closely adjacent to the forward path of the slugs 17 cast in the mold 18 as the latter is moved from the position in which it is shown in Fig. 2 to that in which it is shown in Fig. 3. This pivoted plate 12 is adapted to be turned on its pivot 13 in opposition to the influence of the spring 15 by the knife-releasing projections next to be described, cast for that special purpose on the said slugs.

In certain matrices employed for casting slugs bearing characters of the larger body dimension, for example, punctuation matrices 19 such as are shown in Figs. 5 and 6 or en spaces 20 such as are shown in Fig. 7 or character matrices having descenders such as the "Q's," there are provided supplemental cavities 21 which are instrumental in producing the aforesaid overhanging knife-releasing projections 22 on what may be regarded as the descender side of the resultant type character cast or space produced. Each of these supplemental cavities 21 is divided from the main formative cavity 23 by a spur 24 which leaves the aforesaid resultant projection 22 attached to the slug 17 by a thin and readily breakable neck 25.

When the supplemental cavities 21 are formed on the en spaces 20, as shown in Fig. 130

7, these latter are provided with other cavities 26 aligned with the formative cavities 23 of the character matrices and divided from the said supplemental cavities by spurs 24 6 as in the example shown in Figs. 5 and 6, but the cavities 26 are not sufficiently deep to produce surfaces of printing height; consequently the projections cast on the slugs in these cavities cannot make impressions on 10 the printed sheet, the said projections serving merely to provide a temporary support for the overhanging knife-releasing projections 22 cast thereon.

In the case of slugs having characters of 15 the smaller body dimension, there is no necessity for the knife 1 to be moved from its lowest position and consequently there are no projections 22 cast on those slugs and therefore nothing to cause the plate 12 to 20 turn on its pivot; consequently during the forward movement of the mold wheel, the latch 11, then in its forward or operative position, is not disturbed, and for the time being retains the knife 1 in its lowermost position, with the section 3 thereof in position to effect the trimming of the said slugs.

For effectively carrying out this invention there need not be more than one of the 25 projections 22 cast on each slug having characters of the larger body dimension, and if the line, in connection with which the projection 22 is cast, contains no punctuation marks or descenders, then the said projections 22 can be produced from one of the 30 aforesaid en spaces 20 which can be inserted into the composed line of matrices at or near either end thereof.

To enable the machine to trim slugs of 35 varying body dimensions, that is to say, dimensions intermediate the two extremes provided for by the two knife sections 2, 3, of relatively fixed position as in the before-described example, one of the sections may be adjustable relative to the other in lateral direction so that slugs of any body dimension between maximum and minimum can be dealt with. In Figs. 9 to 12 are 40 shown three different means by which the just-named result can be attained; this adjustment, however, in these four figures is shown as restricted to the upper section 3, but it is to be understood that if desired corresponding adjustment of the lower section 2 may be provided for, as an alternative to or in conjunction with, the adjustability of the upper section 3. In each of the arrangements now under review the knife 1 is formed of two main portions 26 and 27, the former bearing the before-described knife section 2 and the latter bearing the knife section 3.

In the construction shown in Fig. 9 the knife portion 27 is capable of being secured in different positions on the portions 26, by 55 means of one or more clamping screws 28,

and when these screws 28 are released the part 27 can be finally adjusted on the part 26 by means of set screws 29 threaded in the last named part and bearing against the right-hand edge of the part 27. After 70 such adjustment by the set-screws 29 the two parts 27, 26 can be rigidly secured together by tightening the clamping screws 28.

In the construction shown in Figs. 10 and 11 the part 27 is held to the part 26 by two screws 30 threaded into the latter part, the heads of which are counter-sunk into the former part, and the part 26 has threaded into it the stems of set-screws 31, the heads 32 of which abut 80 against the right-hand side of the part 27, these set-screws 31 being adjusted from the right-hand side of the knife by a screwdriver engaging with slots or nicks (see particularly Fig. 11) in the right-hand ends 85 of their stems. To enable the part 27 to be adjusted relatively to the part 26 the screws 30 are released and the set-screws 31 are screwed more or less into the part 26 to obtain the desired relative positions between 90 the operative faces 3, 2 of the parts 27, 26, and after this adjustment has been secured the two parts may be firmly secured in the positions so arrived at by tightening the screws 30, which at the same time serve to 95 lock the set-screws 31 against accidental rotation.

In the construction shown in Fig. 12 the part 27 is held to the part 26 by two screws 30 the stem of each of which is threaded into a bush 33 which is itself provided with an external screw thread and screwed into the part 26, these bushes being provided with nicks 34 whereby they can be adjusted so as to project more or less from the part 26. To 100 lock the bushes in any position to which they may be adjusted in the part 26 there are provided short headless screws 35 threaded into the same holes as those in which the said bushes are themselves adjustable, and when 105 those screws are jammed against the right hand side of the bushes 33, both such parts are locked against accidental displacement. In this arrangement the left-hand ends of the bushes 33 serve for supporting the part 27 110 against the tightening pressure of the screws 30, in the same manner as do the screw-heads 32 in the example illustrated in Figs. 10 and 11.

Having described our invention we declare that what we claim and desire to secure by Letters Patent is:—

1. In or for a typographical casting machine, a slug trimming knife having a plurality of independently usable trimming 125 edges located in different planes so as to act upon different slugs of unlike dimensions.

2. In or for a typographical casting machine, a slug trimming knife having a plurality of independently usable trimming 130

- edges located in different parallel planes so as to act upon different slugs of unlike dimensions.
3. In or for a typographical casting machine, a slug trimming knife having a plurality of independently usable trimming edges located in different planes and adapted to trim the body portions of different slugs of unlike dimensions.
- 10 4. A slug trimming knife for typographical casting machines comprising a plurality of independently usable sections arranged end to end and adjustable to different relative positions, and means for maintaining the sections in their different adjusted positions.
- 15 5. A movable slug trimming knife for typographical casting machines comprising a plurality of independently usable sections arranged end to end, one of said sections being carried by another and adjustable to different operative positions with respect thereto.
- 20 6. In a slug-trimming knife for a typographical casting machine, the combination of a plurality of independently usable sections arranged end to end with trimming edges in respectively different planes and adapted to trim slugs of respectively different body dimensions, and means adapted to vary the relative positions of the said sections for the purpose of trimming slugs of correspondingly varying body dimensions.
- 25 7. In a slug-trimming knife for a typographical casting machine, the combination of a plurality of independently usable sections arranged end to end and relatively adjustable in lateral direction, and screws adapted respectively to move one of such sections laterally in opposite directions relatively to the other section.
- 30 8. In a typographical casting machine, the combination with a trimming knife having a plurality of sections with trimming edges in respectively different planes and adapted to trim slugs of respectively different body dimensions, of means adapted to move the said knife longitudinally to bring its sections alternatively into operative position.
- 35 9. In a typographical casting machine, the combination with a trimming knife having a plurality of sections with trimming edges in respectively different planes and adapted to trim slugs of respectively different body dimensions, the said knife being adjustable longitudinally to bring one or another of its sections into active position, of a device adapted to lock the knife against longitudinal movement.
- 40 10. In a typographical casting machine, the combination with a trimming knife having a plurality of sections with trimming edges in respectively different planes and adapted to trim slugs of respectively different body dimensions, the said knife being ad-
- justable longitudinally to bring one or another of its sections into active position, of a device adapted to lock the knife against longitudinal movement, and means adapted to effect the release of the said locking device. 70
11. In a typographical casting machine, the combination with a longitudinally movable trimming knife having a plurality of sections with trimming edges in respectively different planes and adapted to trim slugs of respectively different body dimensions, of a device adapted to lock the knife against longitudinal movement, and means operated by the slug to be trimmed adapted to effect the release of the said locking device. 80
12. In a typographical casting machine, the combination with a longitudinally movable slug-trimming knife having a plurality of sections with trimming edges in respectively different planes, of a latch adapted to lock the knife against longitudinal movement, means constantly tending to hold the latch in, or return it to, its knife-locking position, and a device operatively connected with the said latch and adapted to be operated by an overhanging projection on a slug advancing to be trimmed, so as to effect the release of the latch from its knife-locking position. 85
13. In a slug casting machine, the combination of a slug trimming knife having a plurality of cutting edges arranged in different planes, and means whereby one or another of said edges may be brought into active position. 90
14. In a slug casting machine, the combination of a slug trimming knife comprising a plurality of sections having their cutting edges arranged in different planes, and means whereby the knife may be adjusted vertically to bring one or another of said sections into active position. 95
15. In a slug casting machine, the combination of a slug trimming knife having a plurality of cutting edges arranged in different planes, and means for bringing one or another of the cutting edges into active position, the said means being controlled by a cast slug. 100
16. In a typographical casting machine, the combination of a mold wherein the slug is cast, and trimming mechanism adjustable to different operative positions to correspond to the body dimension of said slug, said mechanism being controlled in its adjustment by the slug itself. 110
17. In a typographical casting machine, the combination of a mold wherein the slug is cast, and trimming mechanism comprising a pair of knives, one of which is adjustable to different operative positions relatively to the other to vary the distance between them to correspond to the body dimension of said slug, the adjustment of said knife being controlled by the slug itself. 115
18. In a typographical casting machine, the combination of a mold wherein the slug is cast, and trimming mechanism comprising a pair of knives, one of which is adjustable to different operative positions relatively to the other to vary the distance between them to correspond to the body dimension of said slug, the adjustment of said knife being controlled by the slug itself. 120
19. In a typographical casting machine, the combination of a mold wherein the slug is cast, and trimming mechanism comprising a pair of knives, one of which is adjustable to different operative positions relatively to the other to vary the distance between them to correspond to the body dimension of said slug, the adjustment of said knife being controlled by the slug itself. 125
20. In a typographical casting machine, the combination of a mold wherein the slug is cast, and trimming mechanism comprising a pair of knives, one of which is adjustable to different operative positions relatively to the other to vary the distance between them to correspond to the body dimension of said slug, the adjustment of said knife being controlled by the slug itself. 130
21. In a typographical casting machine, the combination of a mold wherein the slug is cast, and trimming mechanism comprising a pair of knives, one of which is adjustable to different operative positions relatively to the other to vary the distance between them to correspond to the body dimension of said slug, the adjustment of said knife being controlled by the slug itself. 135

18. In a typographical casting machine, the combination of a mold wherein the slug is cast, and a matrix adapted to be presented in operative relation to the mold, the said matrix being provided with a notch or cavity to produce on the slug a plain overhanging projection of less than type height, with a slug trimming mechanism adapted to trim the cast slug and controlled in its trimming action by the overhanging projection.

19. In a typographical casting machine, the combination of a mold wherein the slug is cast, and a matrix adapted to be presented in operative relation to the mold, the said matrix being provided with a notch or cavity

ity, and spur located therein so as to produce on the slug an overhanging projection connected therewith by an easily severable neck, with a slug trimming mechanism controlled by said overhanging projection 20 and adapted to trim the cast slug and to cut through the neck portion during the trimming action.

In witness whereof we have hereunto set our hands in the presence of two witnesses. 25
